(57) **CLAIM**

The ornamental design for a hose holder, as shown and described.

DESCRIPTION

The article in which the claimed design is embodied is a hose holder intended for use in holding a hose (e.g., a garden or yard watering hose) while the hose is spraying water out of the hose in a desired direction. Environmentally but not claimed, the hose holder may be mounted on a post.

FIG. 1 is a top, back, left side perspective view of a hose holder showing my new design;

FIG. 2 is a left side elevational view thereof on a reduced scale;

FIG. 3 is a right side elevational view thereof on a reduced scale;

FIG. 4 is a back end elevational view thereof;

FIG. 5 is a front end elevational view thereof;

FIG. 6 is a top plan view thereof;

FIG. 7 is a bottom plan view thereof; and,

FIG. 8 is a left side elevational view of the hose holder on a reduced scale shown in a condition of use.

The portions of FIGS. 1–5 and 7–8 that are drawn with broken lines are for environmental purposes only, and do not constitute part of the claimed design.
